His Attorney.

UNITED STATES PATENT OFFICE.

ARCHIE W. GIBBONS, OF KANSAS CITY, MISSOURI.

AUTOMOBILE FLOW-LINE PROTECTOR.

1,397,630.

Specification of Letters Patent.

Patented Nov. 22, 1921.

Application filed March 21, 1921. Serial No. 454,326.

To all whom it may concern:

Be it known that I, ARCHIE W. GIBBONS, a citizen of the United States, residing at Kansas City, in the county of Jackson and 5 State of Missouri, have invented a certain new and useful Improvement in Automobile Flow-Line Protectors, of which the following is a specification.

My invention relates to improvements in 10 automobile flow line protectors.

The object of my invention is to provide a novel means for rendering the fuel flow line of an automobile inoperative when the car is not in use, thereby preventing unauthorized use of the car.

My invention provides a flow line having an easily removable and replaceable section.

My invention provides further novel means for preventing the substitution of another section for the removable section when the latter has been removed.

My invention provides further a device which is simple in construction, cheap to make, durable, not liable to get out of order, 25 which may be readily applied to automobiles now in use, and which is readily accessible for manipulation by a person in the car.

The novel features of my invention are hereinafter fully described and claimed.

30 In the accompanying drawing, which illustrates the preferred embodiment of my invention,

Figure 1 is a side elevation of my improved device shown mounted in a car, a 35 portion of the body of which is shown in vertical section.

Fig. 2 is an enlarged central vertical sectional view of the housing and parts connected therewith.

40 Fig. 3 is a horizontal sectional view on the line 3—3 of Fig. 4.

Fig. 4 is a cross section on the line 4—4 of Fig. 2.

Similar reference characters designate 45 similar parts in the different views.

1 designates an ordinary supply tank and 2 a carbureter of an automobile. 4 and 3 designate respectively two sections of a fuel flow line conductor connected to the tank 1 and the carbureter 2.

55 5 designates the body of a housing having its ends connected to the sections 3 and 4 and having a lateral opening adapted to be closed by a closure 6 hinged by a longitudinal pintle 7 at one longitudinal edge to the body 5. The latter is provided at the oppo-

site side with a longitudinal laterally extending flange 8 having a hole 9 adapted to register with a hole 10 in a longitudinal flange 11 of the closure 6. The holes 9 and 10 are adapted to receive therethrough the hasp 12 of a padlock 13.

Insertible into and removable from the housing through the lateral opening in the latter, when the closure 6 is open, is an intermediate flow line section comprising preferably the following described parts.

Two tubular members 14 and 15 each having imperforate sides, are slidably mounted one in the other, the outer ends of said members being preferably conical and fitted respectively to conical seats 16 and 17 provided in the housing body 5 adjacent to the ends thereof. The member 15 is provided with an axial opening 18 adapted to communicate with the section 4 and has mounted in it a central longitudinal tube 19 which is slidable in a central opening 20 in the member 14. The opening 20 is adapted to communicate with the section 3.

The member 14 is provided with a central inwardly extending tubular boss 21 which is externally threaded and has fitted thereon a stuffing box 22 which encircles the tube 19 and holds packing material 23 against the boss 21. The member 15 is normally forced to the right, as viewed in Fig. 2, by a coil spring 24 which encircles the boss 21 and tube 19 and bears at one end against the member 14, and at its other end against a collar 25 rigidly secured to the tube 19.

The coil spring 24 normally holds the members 14 and 15 tightly against the conical seats 16 and 17 respectively.

In order that the intermediate section may be contracted in length so as to be insertible and removable through the opening in the side of the body 1, the member 15 has mounted in it an inwardly extending pin 26 which extends into a spiral slot 27, provided in the member 14. A flange 26' extends outwardly laterally from the member 15, as shown in Fig. 4, so that it will serve as a finger hold for turning the member, so as to compress the spring 24 and contract the intermediate section, so that the members 14 and 15 can be withdrawn when the closure 6 is in the open position.

Fixed in the housing body 5 is an inwardly extending pin 28, which extends 110 into a longitudinal slot 29 in the member 14. The pin 28 permits longitudinal move-

ment of the member 14 but holds the member 14 from axial turning.

The housing body 5 is preferably mounted on the upper side of the floor 30 of the body 31 of the automobile. The section 3 may be provided above the floor 30 with a shut off cock 32 by which, when the members 14 and 15 are to be removed, the flow from the tank 1 may be shut off in the section 3.

10 By having the housing body 5 and the shut off cock 32 located in the body of the machine above the floor, the device may be operated by a person sitting in the machine.

For permitting liquid fuel to escape from 15 the housing 5, in case that the members 14 and 15 are removed and the cock 32 were opened, the body 5 is provided on its under side with a large hole 33, Fig. 2.

In the operation of my invention, with 20 the cock 32 opened and the parts in the position shown in the drawing, the liquid fuel will pass from the tank 1 through the section 3, thence through the hole 20, tube 19, hole 18 and section 4 to the carbureter 2.

25 When it is desired to remove the intermediate section of the flow line, the padlock is removed, and the cover 6 swung to the open position, upon which the member 15 is revolved on the member 14, thereby drawing 30 the latter into the member 15, thus shortening the intermediate section, so that the members 14 and 15 may be withdrawn from the housing body 5. The cover 6 may then be closed and locked in the closed position by the padlock 13. Previous to the 35 removal of the members 14 and 15, the cock 5 is closed.

With the members 14 and 15 removed, the carbureter 2 will be cut off from the tank 1 40 so that the engine of the car can not be operated by an unauthorized person. By having the cover 6 closed and locked, a temporary connection can not be made between the sections 3 and 4. In case any one tries 45 to supply the carbureter with fuel by opening the cock 32, the liquid fuel will pass out of the housing body 5 through the opening 33, which is of sufficient size to discharge therethrough any liquid fuel which may be 50 discharged into the body 5 from the section 3.

When it is desired to again use the machine, the padlock 13 is removed, the cover 6 swung to the open position, and the members 14 and 15, in the contracted position, are slipped into the body 5 with the pin 28 extending into the slot 29. The member 15 is then turned by means of the flange 26 to the position shown in Figs. 2 and 3, in 60 which position the members 14 and 15 will have their conical ends respectively fitted in the seats 16 and 17, thereby reestablishing the continuity of the flow line. The cover 6 may then be closed and locked to prevent 65 tampering with the members 14 and 15.

I do not limit my invention to the structure shown and described, as many modifications, within the scope of the appended claims, may be made without departing from the spirit of my invention.

70

What I claim is.

1. In a device of the kind described, the combination with the floor of an automobile, of a fuel flow line conductor having a removable section disposed above said floor, 75 substantially as set forth.

2. In a device of the kind described, the combination with the floor of an automobile, of a fuel flow line conductor having a removable section above the floor, a supply 80 tank a carbureter with which the tank is connected by said conductor, and a shut off cock in said conductor above said floor intermediate of the tank and said removable section, substantially as set forth.

85

3. In a device of the kind described, the combination with a fuel supply tank and a carbureter, of a flow line conductor connecting the tank and carbureter and comprising two sections respectively connected with the 90 tank and carbureter and provided respectively with seats, and an intermediate section which is extensible and contractible and which has its ends respectively fitted to said seats, and yielding means for normally forcing said ends against said seats, substantially as set forth.

95

4. In a device of the kind described, the combination with a supply tank and a carbureter, of a fuel flow line conductor comprising two sections respectively connected with said tank and carbureter, and an intermediate section comprising two tubular members slidably fitted one in the other and arranged to be respectively removably fitted 100 in said seats, and means for normally forcing said members against said seats, substantially as set forth.

105

5. In a device of the kind described, the combination with a supply tank and a carbureter, of a fuel flow line conductor connecting the tank and carbureter and comprising two sections respectively connected with the tank and the carbureter, a housing connecting said sections, and an intermediate 110 tubular section arranged to be removably fitted in said housing and to be respectively connected with said sections, substantially as set forth.

115

6. In a device of the kind described, a 120 housing adapted to be connected at its ends to two sections respectively of a fuel flow line conductor and having two seats respectively adjacent to its ends, and a tubular section adapted to be removably mounted in said housing with its ends respectively fitted to said seats, substantially as set forth.

125

7. In a device of the kind described, a housing having its ends provided with means for being respectively connected to two sec- 130

- tions of a fuel flow line conductor and having respectively adjacent to its ends two seats, and having a lateral opening and a closure from said opening, and having means 5 for releasably locking the closure in the closed position, and a tubular flow line section arranged to be inserted into or removable from said housing through said opening and having its ends respectively fitted 10 to said seats, and adapted to respectively communicate with said sections, substantially as set forth.
8. In a device of the kind described, a housing having means for being inserted in a fuel flow line conductor and provided adjacent to its ends with two seats, and an intermediate section comprising two tubular members slidably fitted one in the other and arranged to be inserted into and removed 20 from the housing, said members having their ends respectively fitted to said seats, substantially as set forth.
9. In a device of the kind described, a housing adapted to be inserted in a fuel flow line conductor and provided adjacent to its ends with two seats, an intermediate section comprising two tubular members slidably fitted one in the other and respectively fitted to said seats and arranged to be inserted into 30 and removed from said housing and adapted to communicate with said conductor when mounted in said seats, and yielding means for normally forcing said members against said seats, substantially as set forth.
- 35 10. In a device of the kind described, a housing having means for being inserted in a fuel flow line conductor and having adjacent to its ends respectively two seats, and provided with an opening and a closure for 40 said opening, and means for releasably locking the closure in the closed position, an intermediate section comprising two tubular members slidably fitted one in the other and respectively fitted to said seats, and insert- 45 ible into and removable from said housing through said opening, and yielding means for normally forcing said members against said seats, substantially as set forth.
- for normally forcing said members against said seats, in which last named position, said members are adapted to communicate with said flow line conductor, substantially as set forth.
11. In a device of the kind described, a housing having means for being connected at its ends respectively with two sections of a fuel flow line conductor and provided adjacent to its respective ends with two seats and having a lateral opening, an intermediate section comprising two tubular members slidably fitted one in the other and respectively fitted to said seats and provided with connecting means by which said intermediate section is expanded and contracted when one of said members is turned alternately in opposite directions on the other member, said members when mounted in said seats being 60 adapted to communicate with said conductor, said members being insertible into and removable from said housing through said opening, a closure for said opening, and means for releasably locking the closure in 65 the closed position, substantially as set forth.
12. In a device of the kind described, a housing having means by which its ends are adapted to be connected with two sections of a fuel flow line conductor and having adjacent to its respective ends two seats, and having a lateral opening, a closure for said opening and a drain outlet, releasable means for locking the closure in the closed position, and an intermediate section comprising two 70 tubular members slidably fitted one in the other and respectively fitted to said seats and adapted, when mounted in said seats to communicate with said sections, and insertible into and removable from said housing 75 through said lateral opening, and a spring arranged to normally force said members against said seats, substantially as set forth.

In testimony whereof I have signed my name to this specification.

ARCHIE W. GIBBONS.
